UNITED STATES PATENT OFFICE.

CLARENCE A. BODDIE, OF PITTSBURGH, PENNSYLVANIA, ASSIGNOR TO WESTINGHOUSE ELECTRIC & MANUFACTURING COMPANY, A CORPORATION OF PENNSYLVANIA.

RELAY.

Application filed May 4, 1920. Serial No. 378,731.

To all whom it may concern:

Be it known that I, CLARENCE A. BODDIE, a citizen of the United States, and a resident of Pittsburgh, in the county of Allegheny and State of Pennsylvania, have invented a new and useful Improvement in Relays, of which the following is a specification.

My invention relates to relays and particularly to polarized relays.

One object of my invention is to provide a relay structure that shall be simple and relatively inexpensive in construction and that shall be controlled either in accordance with the power supplied by a circuit or in accordance with the direction of current flowing through said circuit.

In many regulator systems, it is desirable to provide a relay structure which is operated directly in accordance with the watts supplied by a circuit. Thus, for example, in an electric furnace system, it is very desirable to operate a relay in accordance with the power supplied to an electrode in order to effect control of such electrode in accordance with the delivered watts. It is also often desirable to provide a polarized relay structure that shall be operated in accordance with the direction of current flow through a circuit. Other applications of the relay described herein will be apparent from the following specification.

Preferably, my relay structure comprises a movable core armature, which is controlled by three stationary coils. Two of the coils are oppositely wound and are connected in series circuit relation and the third coil is located between the two series-connected coils. The core armature, which is located within the coils, is polarized by the central coil in order to be operated in accordance with the direction of current flow through the two series-connected coils. The central coil is centrally located with respect to the core armature and can produce no movement of the core armature without the aid of the series-connected coils. The two series coils are symmetrically located, with respect to the core armature, and being wound in opposite directions, it is apparent that the series-connected coils can effect no movement of the core member without the aid of the polarizing winding. When the three coils are simultaneously energized, the magnetic field produced by the central winding co-operates with the magnetic fields pro-

duced by the two series-connected coils for moving the core armature in a direction determined in accordance with the directions of current flow through the coils. The direction of movement of the core armature may be changed by reversing the current flow either through the central coil or through the two series-connected coils.

In operating the relay structure in accordance with the watts delivered by a supply circuit, the central winding is preferably energized in accordance with the potential obtaining on such circuit and the series-connected windings are energized in accordance with the value of the current flowing through the circuit. Thus, the core armature is operated directly in accordance with the watts supplied by the circuit.

In the accompanying drawing, Fig. 1 is a diagrammatic view of a relay constructed in accordance with my invention and connected to a supply circuit, and Fig. 2 is a diagrammatic view of the relay structure indicating the magnetic fields produced by the various coils.

Referring to the drawing, a relay 1 comprises a core armature 2 and coils 3, 4 and 5. The coil 4 is centrally located with respect to the core armature 2 and the coils 3 and 5 are located upon opposite sides of the coil 4. The coils 3 and 5, which are connected in series-circuit relation, are wound in opposite directions and comprise equal number of turns.

The core armature 2 is pivotally connected to a contact arm 6 which selectively connects a conductor 7 to conductors 8 and 9 in accordance with the operation of the relay structure. A spring member 10 is provided for so counter-balancing the weight of the core member 2 as to maintain the contact arm 6 in a neutral position, as shown, when the coils 3, 4 and 5 are normally energized. The coil 4 is connected across a supply circuit comprising conductors 11 and 12 in order to be energized in accordance with the voltage obtaining in the supply circuit and the coils 3 and 5 are connected to a current transformer 13 in order to be energized in accordance with the current flow through the supply circuit. The coils 3, 4 and 5 are stationary and have no movement relative to each other.

The coil 4 is assumed to produce a magnetic field which is represented by the ar-

- rows 14 in Fig. 2 of the drawing. The coil 3 is assumed to produce a magnetic field which is represented by the arrows 15 and the coil 5 is assumed to produce a magnetic field which is represented by the arrows 16. If the coil 4 is energized alone and the two coils 3 and 5 are de-energized, it is apparent that the magnetic field produced will effect no movement of the core armature 2 relative to the coil 4. However, the coil 4 produces a magnetic field which polarizes the core armature 2 in accordance with the direction of current flow through the coil.
- If the two coils 3 and 5 are energized and the coil 4 is de-energized, it is apparent no movement of the core armature 2 relative to the two coils will be effected. The two coils 3 and 5 are symmetrically disposed relative to the core armature 2, and, inasmuch as the two coils are wound in opposite directions, it is apparent the magnetic fields produced are neutralized. In case the three coils are simultaneously energized, the core armature 2 is moved in accordance with the direction of current flow through the coils. If the coils are energized as assumed in the structure shown in Fig. 2, the core armature 2 is moved upwardly. The magnetic field produced by the coil 4 repels the magnetic field produced by the coil 3 and attracts the magnetic field produced by the coil 5. Accordingly, it is apparent that the three coils produce magnetic fields which jointly tend to move the core armature 2 in an upward direction. If the current flow through either the coil 4 or through the coils 3 and 5 be reversed, it is apparent that the direction of movement of the core armature 2 would be changed.
- In the system shown in Fig. 1, the relay structure 1 is operated directly in accordance with the watts supplied by the circuit comprising conductors 11 and 12. When normal power is supplied by the circuit the core armature 2 and the contact arm 6 are retained in a neutral position with the conductor 7 disconnected from the conductors 8 and 9. Such position is maintained by the magnetic action of the coils assisting the spring 10 in supporting the core armature 2. If more than a normal number of watts is supplied by the circuit the contact arm 6 is raised to connect the conductor 7 with conductor 8. The spring 10 has not sufficient strength of itself to support the core armature 2. Consequently, if less than a normal number of watts is supplied by the conductors 11 and 12, the core armature 2 and the contact arm 6 are allowed to drop and effect connection between conductors 7 and 9.
- In order to more clearly show that the core member 2 is operated directly in accordance with the watts passing through the circuit comprising conductors 11 and 12, the magnetic effects of the coils 3, 4 and 5 will

be considered in detail. If the core member 2 were controlled solely by the current coil 3, it is apparent it would be moved in a accordance with a constant and the square of the value of the current flowing through the coil 3. Assuming P_3 to be the magnet force of the coil 3 acting on the core member 2, K_3 to be a constant for such coil and I to be the current flowing through the coil 3, then we have the equation $P_3 = K_3 I^2$. In the same manner, the coil 5 exerts a magnetic force $P_5 = K_5 I^2$. Inasmuch as the two coils 3 and 5 are wound with an equal number of turns and are connected in series circuit relation, it is apparent the force is equal and opposite to the force P_3 .

The middle coil 4 is centrally located and produces no magnetic force which acts directly to effect movement of the core member 2. However, the coil 4 produces a magnetic field H which reacts upon the field produced by the coils 3 and 5 to effect movement of the core member 2. The magnetic field H produced by the core 4 varies in accordance with the voltage E of the supply circuit and, accordingly, it may be stated that the magnetic field H equals a constant $K_4 \times E$. The magnetic fields produced by the coils 3 and 5 vary in accordance with the current I passing through such coils. Accordingly, it may be stated that the magnetic field produced by the coil 4 reacts upon the magnetic fields produced by the coils 3 and 5 to produce a magnetic effect or force which is equal to $K_4 E I$. Consequently, the combined magnetic effects P of the three coils is equal to $K_3 I^2 - K_5 I^2 + K_4 E I$. Inasmuch as the quantities $K_3 I^2$ and $K_5 I^2$ are equal and opposite, it is apparent the force pull of the coils upon the core member is equal to $K_4 E I$. Thus, it is apparent the core member 2 is moved in accordance with the watts flowing through the supply circuit comprising conductors 11 and 12.

It also will be obvious that the relay illustrated in the drawing may be equally well used for power-factor correction, maintaining the same relation between the coils 4 and 5. For example, an application of this invention to a three-phase delta-connected winding may be assumed.

It is well known that the vector line representing the current at the apex of a triangle will be at right angle to the vector line representing the voltage across the base of the triangle at 100% power factor. Hence, if the voltage coil 4 is connected across the base of the triangle, and the current coils 3 and 5 connected to the apex of the triangle, the contact arm 6 will occupy a neutral position at 100% power factor. If the power factor should vary from 100%, the variation would produce a force which, acting against the potential of the relay, would either pull or push the

contact arm 6 in such manner to effect the fixed coils oppositely wound about said core on opposite sides of said first-named coil, said three coils cooperating to actuate said core member in accordance with the phase angle between the sources of energization of said coils.

In other words, the current I in a transformer connected at the apex of the triangle, times the voltage E represented by the base of the triangle, times the cosine of the angle therebetween at 100% power factor equals zero. Hence, the magnetic pull on the core 10 2 of the relay at this time will be zero.

The power factor at which the relay will be operative may be adjusted by cross-connecting series transformers in circuit with each of the windings, and connecting the potential winding to an auto transformer.

Modifications in the structure and in the arrangement and location of the parts may be made within the spirit and scope of my invention, and such modifications are intended to be covered by the appended claims.

I claim as my invention:—

1. In a system comprising a source of alternating current, a movable core member, a polarizing winding for magnetizing said core member and for normally holding the core member centrally thereof, a pair of windings symmetrically placed with respect to said polarizing winding for reacting upon the magnetic field of said polarizing winding for moving the core member in accordance with the variation in phase relation of the current in said polarizing winding and the current in said pair of windings.

2. A relay comprising a movable core member and three fixed coils wound about said member, means for energizing the middle one of said coils for magnetizing said core member and for normally holding said core member centrally thereof, means for energizing the other coils for varying the position of the maximum flux density with respect to the position of said coils for varying the position of said core member.

3. A watt relay comprising a movable core member, a voltage coil for magnetizing said core and for normally holding the core centrally thereof, and a pair of current coils symmetrically disposed with respect to said voltage coil and connected in opposition to each other, said coils cooperating to actuate said core in direction and degree in accordance with the energization of said coils.

4. In a system comprising a source of alternating current, a relay comprising a movable core member, a fixed coil wound about said core for normally holding the core member centrally thereof, and two

fixed coils oppositely wound about said core on opposite sides of said first-named coil, said three coils cooperating to actuate said core member in accordance with the phase angle between the sources of energization of said coils.

5. A relay comprising three coils placed along substantially the same axis, a core armature within said coils, two circuits for said relay, one of said circuits comprising the central one of said three coils, the other circuit comprising the other two of said coils differentially related to each other so that the normal position of said core caused by the energization of either of said two circuits will be substantially the same, and the variation of said core from said neutral position will be responsive to the energization of said circuits.

6. In combination, a circuit, a plunger-type relay comprising a movable core member and three windings associated therewith, two of said windings being differentially-connected, and means for energizing said windings in accordance with the voltage and current in said circuit to actuate said core member in accordance with the direction of power flow therethrough.

7. In combination, a circuit, a plunger-type relay comprising a movable core member and three windings associated therewith, two of said windings being differentially connected and disposed at the ends of said core member, and means for energizing said windings in accordance with the voltage and current in said circuit to actuate said core member in accordance with the amount and direction of power flow therethrough.

8. In combination, a power circuit, a plunger type relay comprising three coils placed along substantially the same axis, a core member movable within said coils, two circuits for said relay, one of said relay circuits comprising the central one of said three coils, the other of said relay circuits comprising the other two of said coils differentially related, and means for connecting said relay circuits to said power circuit to be energized in accordance with the voltage and with the current of said power circuit to actuate said core member in accordance with the direction of power flow therethrough.

In testimony whereof, I have hereunto subscribed my name this 29th day of April, 1920.

CLARENCE A. BODDIE.
